GARMENT HANGER FOR A DISPLAY RACK

Maurice Cohen, Miami, Fla.

Application July 16, 1956, Serial No. 42,255

Term of patent 14 years

(Cl. D80—10)

Fig. 1 is a side elevational view of a garment hanger for a display rack showing my new design;

Fig. 2 is a top plan view of a garment hanger for a display rack, and

Fig. 3 is a vertical sectional view taken along line 3—3 in Fig. 1.

I claim:

The ornamental design for a garment hanger for a display rack, as shown.
